STAND FOR DISPLAYING AND MERCHANDISING SUNGGLASSES OR THE LIKE

William G. Pacelli, Leominster, Mass., assignor to Foster
Grant Co., Inc., Leominster, Mass., a corporation of Delaware

Filed Oct. 3, 1963, Ser. No. 77,009

Term of patent 14 years

(Cl. D80—9)

FIG. 1

Des. 199,655

PAGE 2

FIG. 2

FIG. 1 is a side perspective view of a stand for displaying and merchandising sunglasses or the like, showing my new design;

FIG. 2 is a plan view thereof;

FIG. 3 is a side perspective similar to FIG. 1 with sectional portions of the stand cut away to show the interior thereof to show greater clarity.

This application is a continuation-in-part of my co-pending application, Serial No. D. 62,363, filed October 3, 1960, now abandoned.

I claim:

The ornamental design for a stand for displaying and merchandising sunglasses or the like, substantially as shown.
